UNITED STATES PATENT OFFICE.

FRANCES JOHNSON, OF CHICAGO, ILLINOIS.

DESIGN FOR A DOLL.

58,385.

Specification for Design. Patented July 12, 1921.

Application filed December 6, 1920. Serial No. 428,825. Term of patent 7 years.

To all whom it may concern:

Be it known that I, FRANCES JOHNSON, a citizen of the United States, residing at Chicago, in the county of Cook and State of Illinois, have invented a new, original, and ornamental Design for Dolls, of which the following is a specification, reference being had to the accompanying drawing, forming part thereof.

The figure is a plan view of a doll, showing my new design.

I claim:

The ornamental design for a doll as shown.

FRANCES JOHNSON.
